DESIGN FOR A CORD FOR TRIMMING AND DECORATING PURPOSES

Charles P. Schlegel, Rochester, N. Y., assignor
to The Schlegel Manufacturing Company,
Rochester, N. Y., a corporation of New York

Application March 9, 1933. Serial No. 47,420

Term of patent 14 years

To all whom it may concern:

Be it known that I, CHARLES P. SCHLEGEL, a citizen of the United States, residing at Rochester, in the county of Monroe and State of New York, have invented a new, original, and ornamental Design for a Cord for Trimming and Decorating Purposes, of which the following is a specification, reference being had to the accompanying drawing, forming a part thereof.

The figure is a side view of an ornamental cord showing the design.

I claim:

The ornamental design for a cord for trimming and decorating purposes, substantially as shown.

CHARLES P. SCHLEGEL.
